UNITED STATES PATENT OFFICE.

LOUIS KESSLER, OF CHICAGO, ILLINOIS, ASSIGNOR TO ROY W. HILL, TRUSTEE.

CONTAINER.

Application filed August 9, 1923. Serial No. 656,561.

My invention relates to improvements in containers, and more particularly to containers for inflammable liquids, such as gasoline or the like.

5 One of the objects of my invention is to provide a container having filling means therefor, which will prevent combustion of the liquid within the can and prevent the passage of flame from the exterior into the 10 can and thus prevent any explosion of the same.

Another object of my invention is to provide a pouring spout for the can, whereby the contents of the can may be emptied, 15 when desired, and means for rigidly holding said spout normally concealed within the filling means in the can.

Many other objects and advantages of the construction herein shown and described 20 will be obvious to those skilled in the art from the disclosures herein given.

To this end my invention consists in the novel construction, arrangement and combination of parts herein shown and described, 25 and more particularly pointed out in the claims.

In the drawings, wherein like reference characters indicate like or corresponding parts.

30 Fig. 1 is a top plan view of my device; Fig. 2 is a longitudinal section thereof taken substantially on line 2—2 of Fig. 1; and

35 Fig. 3 is a section similar to that shown in Fig. 2 with the spout in pouring position.

In the drawings, wherein I have illustrated the preferred embodiment of my invention, 1 indicates a can or container of any suitable size, shape or material, preferably of sheet metal, so as to be light in weight and yet have the desired strength, said can having an aperture 2 arranged through a wall thereof, as for instance at its top wall, as shown in Figs. 2 and 3, and 45 at which the filling device is adapted to be arranged.

A ring or collar member 3 carrying radially spaced perforated tubes 4 and 5 thereon is adapted to be arranged at the opening 50 2 and through which the liquids may be poured into the can. The ring member 3 preferably has an annular groove 6 about its periphery and into which the outer per-

forated tube 4 may be crimped into place to lock it to the member 3.

55

The annular member 3 is threaded along its bore, as at 8, the bore being enlarged toward the outer end and threaded as at 9, the threads 9 being preferably of a greater pitch than the threads 8. A member 10 60 preferably of sheet metal in the shape of the frustum of a cone so as to form a funnel is flanged over the opening 2 at its large end as at 11 and projects inwardly of the can as shown, the collar ring 3 having a flanged head 12 at its outer end to seat within the small end of the funnel 10, and is 65 preferably connected thereto, as by soldering, welding, brazing or the like. It is impossible for any flame to get through the 70 perforated tubes 4 and 5 and ignite the contents of the can and the device is therefore non-explosive.

A cap or closure member 13 preferably having radial wings 14 thereon for gripping engagement, has an annular flange 15 extending axially thereof, said flange being provided with external screw threads 16 of a pitch to cooperatively engage the interior threads 9 of the member 3 and with internal 80 screw threads 23 of the same pitch as those of the threads 8.

A gasket 17 may be interposed between the cap member 13 and the ring member 3 to prevent leakage therewith, and, if desired, 85 a fusible safety plug 18 may be arranged to normally close an aperture 19 through the cap and which is adapted to be automatically loosened from the cap when the heat within the tank reaches a predetermined degree, or when the pressure within the tank 90 exceeds a certain amount.

In order to provide a pouring spout for the can so that the contents of the can may be discharged or delivered into the filling 95 opening of a suitable container, or the like, without any danger of spilling, a spout member 20 in the form of a tube having an enlarged annular head 21 at one end is normally carried by the cap 13, to project within the tubes 4 and 5, the enlarged head 21 having external screw threads 22 thereon to detachably engage with the internal screw threads 23 of the annular flange of the cap.

The pitch of the screw threads 22 and 23 100 is exactly the same as the pitch of the

threads 8, whereby the threaded head 21 may be screwed either into the cap, as shown in Fig. 2, or into the collar 3, as shown in Fig. 3, and in which latter position it is 5 ready for the pouring operation.

It will be noted that when the spout is secured in place, as shown in Fig. 2, it is entirely concealed and will not rattle, and there will be absolutely no danger of the 10 spout becoming displaced and dropping to the bottom of the tubes 4 and 5, or otherwise interfering with its usefulness.

When it is desired to use the spout for pouring, the cap 13 is unscrewed, and it carries the tube 20 therewith. When the cap is 15 removed, the cap and spout are then separated and the spout is then screwed to the position shown in Fig. 3.

When pouring fluids into the can, the 20 member 10 serves as a funnel to more accurately direct the flow thereto and to prevent waste of fluid. The funnel member also serves the additional purpose of providing a recess, wherein the cap 13 may seat 25 so that the top of the cap does not project beyond the top of the can and there is little danger of the cap becoming injured or knocked off in handling.

Having thus described my invention, it is 30 obvious that various immaterial modifications may be made in the same without departing from the spirit of my invention; hence I do not wish to be understood as limiting myself to the exact form, construction, 35 arrangement and combination of parts herein shown and described, or uses mentioned.

What I claim as new and desire to secure by Letters Patent is:

1. In a device of the kind described and 40 in combination, a can having an opening through a wall thereof, a collar arranged at said opening, a perforated tube carried by said collar within the can, a cap removably secured to said collar to close said opening, and a spout detachably secured to the cap and normally carried solely by said cap within said tube and having means cooperable with said collar so as to engage therewith when it is desired to pour from said can.

50 2. In a device of the kind described and in combination, a can having an opening through a wall thereof, a collar arranged at said opening and having a threaded bore therethrough, enlarged at one end, a perforated tube secured to the exterior periphery of said collar and projecting within the can, a closure cap having internal and external threads, the external threads engageable with the threads at the enlarged portion 60 of said bore of the collar, and a spout having an externally threaded end selectively engageable with the internal threads of the cap and with the threads at the smaller end of the bore through the collar.

65 3. In a device of the kind described and in

combination, a can having an opening through a wall thereof, a collar arranged at said opening and having a bore therethrough, enlarged at one end and threaded with differently pitched threads at the enlarged and reduced portions respectively of the bore, a perforated tube secured to said collar and projecting within the can, a closure cap having a flange with internal and external threads, the external threads engageable with the threads at the enlarged portion of said bore of the collar, and a spout having an externally threaded end selectively engageable to seat within the internally threaded flange of the cap and carried thereby or engageable with the threads at the smaller end of the bore through the collar to form a pouring spout for the can.

4. In a device of the kind described and in combination, a can having an opening 85 through its wall, a collar arranged at said opening and having a bore therethrough threaded in two diameters, a closure cap having external threads engageable with the larger diameter of said collar and also having internal threads, and a spout having one end externally threaded and selectively engageable with the internal threads of the cap and with threads of the smaller diameter of said collar so as to be 90 carried by either said cap or collar.

5. In combination, a can having an opening therein, a collar arranged at said opening and provided with screw threads of relatively large diameter and screw threads of relatively small diameter, a cap engageable with the screw threads of larger diameter for closing said opening, said cap being provided with screw threads similar to said screw threads of relatively small diameter 105 and a spout having screw threads engageable with said screw threads of similar and relatively small diameters in said collar and cap, said spout being supported solely by said cap when said spout is in a functionally 110 inoperative position.

6. A can having an opening through its walls, a collar arranged at said opening, a cap engaging said collar for closing said opening, and a spout having means thereon whereby same may be detachably secured to and carried solely by said cap to extend into said can, said means engageable with said collar when the spout is removed from the cap and the can to hold the spout in pouring 115 position.

7. In a device of the kind described and in combination, a can having an opening through its wall, a funnel secured at its large end at said opening and projecting within said can, a tubular collar secured to the smaller end of said funnel, a cap removably engaging said tubular collar to form a closure for said can, and a spout removably engaging and solely supported by said 125 130

cap when in functionally inoperative position and within said can, said spout engageable when in functionally operative position with said tubular collar to secure said spout in position for pouring from said can.

8. In a device of the kind described, and in combination, a can having an opening through its wall, a tubular collar secured to said can at said opening, a cap having 10 means to engage said tubular collar to form a closure for said can, and a spout having

means whereby the same may be detachably secured to, and carried solely by, said cap when in functionally inoperative position within said can, said spout having means 15 attachable to said tubular collar when the spout is removed from the cap to hold said spout in pouring position.

In testimony whereof, I have hereunto signed my name.

LOUIS KESSLER.
